DESIGN FOR A SALT SHAKER OR SIMILAR ARTICLE

Myron A. C. Johnson, Coral Gables, Fla.

Application November 17, 1944, Serial No. 116,395

Term of patent 7 years

(Cl. D44—22)

To all whom it may concern:

Be it known that I, Myron A. C. Johnson, a citizen of the United States, residing at Coral Gables, in the county of Dade and State of Florida, have invented a new, original, and ornamental Design for a Salt Shaker or Similar Article, of which the following is a specification, reference being had to the accompanying drawing, forming part thereof.

Figure 1 is a side elevational view of a salt shaker or similar article, showing my new design.

Figure 2 is an end elevational view thereof.

Figure 3 is an elevational view of the opposite end thereof.

I claim:

The ornamental design for a salt shaker or similar article, as shown.

MYRON A. C. JOHNSON.
